SHIP'S HATCH COVER

John Tutin, London, England

Application February 16, 1937, Serial No. 126,066
In Great Britain February 22, 1936

3 Claims. (Cl. 114—202)

This invention relates to ships' hatch covers. Its principal object is to provide improved means whereby covers or cover-sections of considerable weight can be readily manipulated by hand power. 5 More specifically, the object of the invention is to provide means enabling heavy covers or cover-sections to be lifted from the hatch, transported to a stowage space and rotated into an edge-upwards position for stowage when not in 10 use and these operations to be performed in the reverse order all expeditiously and with a minimum of manual labour.

With these objects in view the invention provides the combination of a ship's hatchway cover 15 having at each of two opposite sides thereof, or of two opposite sides of each section of a sectional cover, a jack-connecting part, which jack-connecting parts are coaxially arranged and are disposed so that their axes lie at approximately 20 the same level as the center of gravity of the cover or cover-section, and two travelling removable and portable lifting jacks (for example screw jacks) having lifting members and cover-connecting parts thereon for interengagement 25 with the jack-connecting parts on the cover, or on all the cover-sections successively, the inter-engaging connecting parts being adapted to permit rotation of the cover, or cover-section, into an edge-upwards position about their common 30 axis.

Preferably said interengaging connecting parts are in the form of lateral projections in the form of spindles on the cover, or cover-sections, and bearings or sockets on the lifting pillars of 35 the jacks but any other convenient construction may be employed. For example, there may be projections on said lifting pillars adapted to enter bearings or sockets on the cover or cover-sections. The said projections and bearings or 40 sockets may be formed integrally with the parts by which they are carried, or be secured thereto (for example by welding) or they may be removably mounted thereon.

45 Two stowage rails are arranged each in spaced parallel relation with one of the track rails at the stowage space alongside which the track rails extend; the spindles, while situated in said bearings, have parts adapted to rest on and be supported by the stowage rails when the cover members have been transported by the lifting jacks 50 along the track rails to the stowage space.

55 According to a feature of the invention, bulb coaming stiffeners are fixed to the sides of the hatchway coaming and are arranged so that the

bulbous portions thereon constitute track rails for the lifting jacks.

In the case of sectional covers, it is preferred to provide a gutter between adjacent cover-sections. 5

One embodiment of the invention will now be described, by way of example, with reference to the accompanying drawings in which:—

Figures 1 and 1a show in side elevation a hatch with a sectional cover in position thereon, 10

Figures 2 and 2a show a plan thereof,

Figure 3 is a sectional elevation on the line 3—3 of Figure 2 but drawn to a larger scale,

Figure 4 is a section on the line 4—4 of Figure 3, 15

Figure 5 is a side elevation drawn to a still larger scale showing one of the lifting jacks applied to a cover-section ready to lift the same,

Figure 6 is a side elevation showing the lifting jack and the cover-section in positions which 20 they occupy when the latter has been carried to the stowage space and turned edge-upwards, and

Figure 7 is a detail view showing a modification hereinafter referred to.

Like reference numerals indicate like parts 25 throughout.

On the drawings the invention is shown applied to a weather deck hatchway of a cargo tramp steamer, only so much of the deck 10 being shown as is necessary to illustrate the invention. 30

The hatchway 11 is situated between a deckhouse 12 and a mast 13. Winches for manipulating the cargo are disposed between the mast and the hatch. The hatch coaming comprises side bulb plates 15 and end bulb plates 16. At a 35 distance below the level of the top of the coaming sufficient to permit the lifting jacks hereinafter described to be applied to the cover-sections, side bulb angle coaming stiffeners 17 are provided. These stiffeners are arranged with the bulbous 40 portions 18 upwards, see Figure 4, for a purpose to be later explained. A similar coaming stiffener 19 is provided along the forward end of the hatch coaming. Between the deckhouse 12 and the hatch is a stowage space 20 in which the cover-sections of the hatch are stowed edge-upwards 45 when removed from the hatch. The side coaming stiffeners 17 are continued past the hatch end adjacent the deckhouse for the extent of the stowage space 20 where each is surmounted by 50 a plate structure 21 having a bulb plate top 22 constituting a stowage rail to support stowed cover-sections in the manner hereinafter explained. The hatch cover consists of a number of steel sections 23 to 29 inclusive placed athwart- 55

ships across the hatchway. The fore and aft widths of the cover-sections 23 to 28 are the same and the half-width of each of these sections is approximately equal to the height of the 5 hatch coaming. The forward cover-section 29 is approximately half the fore and aft width of the other sections to facilitate its being turned edge-upwards in the minimum space available when the sections 23 to 28 have been stowed in the 10 stowage space 20.

Each of the cover-sections is of hollow form and comprises a top plate 30, see Figures 3 and 4, and girder angles 31, 32 and 33 to which the top plate is welded. The angles 31, 32 lie longitudinally of the cover-section, i. e. across the hatch, and the angles 33 lie transversely of the cover-section, i. e. lengthwise of the hatch. All these girder angles are disposed with one flange edge-upwards so as to permit the bottom faces 15 of the other flanges to rest on rubber strips 34 which are interposed between the girder angles and the upper bulbous ends of the coaming plates 15, 16 so as to provide a watertight joint. The cover-sections 23 to 28 are also provided each 20 with an intermediate stiffening girder 35 disposed between and parallel to the girder angles 31, 32. The girder angles 31 of the cover-sections 23 to 28 face inwards and the girder angles 32 of all the cover-sections face outwards. An edge bar 30 is welded to the edge of the bottom limb of each of the girder angles 32 so as to provide a gutter 50 between it and the upstanding limb of the angle and a rubber sealing strip 37 secured to the edge bar 36 is provided between the latter 35 and the adjacent girder angle 31 to provide a watertight joint between the adjacent cover-sections.

The cover-sections may be held in place by any suitable clamping or wedging devices which as 40 they form no part of the present invention which are not shown on the accompanying drawings.

Two travelling removable and portable lifting screw jacks one only of which is seen in Figures 5 and 6, are provided for removing, stowing and 45 replacing the cover-sections. Each cover-section has projecting laterally from each end a hollow spindle 38 supported by a bracket 39 on the girder angles 33. The spindles 38 of each cover-section are coaxial with one another and approximately 50 in line with the centre of gravity of the cover-section. The two lifting jacks are applied to these two spindles respectively and are in charge of two men, one on each side of the hatchway.

The lifting jacks are identical so that a description of one will suffice for both. Each jack is mounted upon a pair of wheels 139 adapted to travel along the tracks provided by the bulbous portions 18 of the side coaming stiffeners 17. The jack body 40 is disposed between the wheels 139 60 and mounted therein is an externally screw-threaded lifting pillar 41 having at its upper end a hollow crutch 42 adapted to engage the corresponding spindle 38 of the cover-section to be manipulated. A screw clamp 43 is provided for 65 securing the spindle and crutch together. The lifting pillar 41 is arranged to be raised and lowered by means of a hand wheel 44 which has fixed to its axle a bevel wheel 45, see Figure 5. Said bevel wheel meshes with a hollow bevel wheel 46 which is constrained against movement 70 in the direction of its axis. Said latter bevel wheel is rotatably mounted on the lifting pillar 41 so that by turning the hand wheel 44, the lifting pillar can be raised or lowered.

75 The operation of removing and stowing the

hatch cover-sections is as follows:—The clamping or wedging devices, if provided, are first released and then the crutches 42 of the screw jacks are slipped on the spindles 38 of the cover section 23 and secured by the screw clamps 43. 5 The cover-section is then raised from its seating on the hatch coaming by turning the jack hand wheel 44 of each jack. When the cover-section has been raised sufficiently, say about 2 inches from the top of the hatch coamings, the pair of 10 jacks and the cover-section they jointly support are rolled along the tracks 18 to a position beyond the hatch end over the stowage space 20. In this position the screw clamps 43 are freed and the cover-section is swung in the jacks through 15 90° to a vertical position. The cover-section is then lowered by turning the jack hand wheels 44 until its spindles 38 rest upon the bulb plate tops 22 of the plate structure 21 at the stowage space, as shown in chain lines in Figure 1, after 20 which the jacks are removed and run back along the tracks 18 to handle successive covers in a similar way. In Figure 3 it is assumed that the cover-sections 23 to 27 have been removed and stowed and one of the jacks is shown in dotted 25 lines in position to raise and remove the next cover-section 28.

Should it be desired, for example during rainy weather, to uncover only a portion of a large hatchway, say the portion covered by the cover-sections 25 and 26, then the cover-sections 23 and 24 may be removed and stowed and cover-sections 25 and 26 be raised, transported and lowered into the positions formerly occupied by cover-sections 23 and 24. 35

In the modification shown in Figure 7, the top plates 30 of adjacent cover-sections are provided along adjacent longitudinal edges with depending flanges 47. Each of these flanges is welded to the inner face of one limb of an angle 48 which 40 is so disposed that said limb will rest on the coaming and the other limb 49 will lie adjacent the corresponding limb of the other angle. The rubber sealing strip 37 is secured to one of the adjacent angle limbs 49. The plate flanges 47 are 45 welded to the angles 48 at such positions as to provide gutters 50 between them and the angle limbs 49. The angles 48 may be bulb angles as shown, or plain angles, or alternatively channels may be employed. In the latter case, the 50 bottom of the channel will rest on the coaming and the gutter will be formed between the plate flange and one side of the channel.

In the construction described above, a stowage space 20 is provided at one end only of the hatch. 55 There may be a stowage space at each end of the hatch to permit some of the cover-sections to be stowed at one end and others at the other end. Alternatively, when the cover-sections are disposed with their longitudinal edges fore and aft 60 of the deck, provision may be made for stowing them at one or both sides of the hatch. In this case, the tracks for the lifting jacks will be provided at the ends of the hatch.

Further, the provision of a stowage space provided with supports, such as the aforesaid rails 22, for the spindles 38 of the cover-sections, is not essential to the invention. The said spindles may be used only for lifting and lowering the cover-sections and for moving them within the 70 boundary of the hatchway, for example to a position whence they can be removed by a derrick for stowage flat on the deck.

Alternatively, the cover-sections may be turned edge-upwards in the jacks when removed to the 75

stowage space and then be lowered in said jacks until the bottom edge rests on the deck, and then be tilted so that they lean against a support, for example the wall of the deck-house 12.

5 Any convenient means may be provided for preventing any substantial endwise and/or side-wise movement of the cover or cover-sections on the hatch due to pitching and/or rolling of the ship. For example there may be provided depending flanges on the cover or cover-sections arranged to lie inside the hatch coaming. In the construction shown on the drawings, flanges 51 are provided on the ends of the cover-sections for preventing endwise movement of the cover-sections individually, and a flange 52 is provided 10 on the outer longitudinal side of the cover-sections 23 and 29 (only the flange 52 on the cover-section 29 is shown on the drawings) for preventing fore and aft movement of the cover as a whole.

20 It will be evident that the invention provides means whereby heavy steel covers can be removed and replaced with ease and rapidity without the provision of derricks and winches.

25 In the appended claims the term "cover member" is intended to include both a one-piece cover for a smaller hatchway and any one of a number of independent cover-sections of a sectional cover which when arranged side by side constitute 30 a cover for a larger hatchway.

I claim:—

1. Apparatus for lifting ship's hatchway cover members from the hatch and transporting them to a stowage space comprising a cover member,

two coaxial jack-connecting parts on opposite sides of the cover member, two travelling removable and portable lifting jacks each having two track wheels, a lifting pillar, and a cover-connecting part on the pillar adapted to engage a 5 said jack-connecting part on the cover member, and two track rails lying at opposite sides of the hatch and extending alongside the stowage space, one track rail for each lifting jack, in combination with two stowage rails arranged each in 10 spaced parallel relation with one of the track rails at the stowage space, which jack-connecting parts are constituted by spindles projecting laterally from the cover member, and which cover-connecting parts are constituted by bearings each 15 for receiving a said spindle adapted to rotate therein, which spindles, while situated in said bearings, have parts adapted to rest on and be supported by said stowage rails.

2. Apparatus for lifting ship's hatchway cover 20 members as set forth in claim 1, wherein the axis of rotation of said spindles extends through the cover member and lies close to the center of gravity thereof, and each track rail is constituted by the bulbous portion of a bulb coaming stiffener 25 fixed one at each side of the hatchway coaming and extending alongside the stowage space.

3. Apparatus for lifting ship's hatchway cover members as set forth in claim 1, wherein the track rails are situated on the side of the hatchway coaming above the deck level, and the stowage rails lie a short distance above the level of the track rails.

JOHN TUTIN.
